SPECTACLE CASE

Erma Spielberg, 41 Union Square, New York, N.Y.

Filed June 24, 1959, Ser. No. 56,522

Term of patent 7 years

(Cl. D57—1)

FIG.1

Fig. 1 is a front elevational view of a spectacle case, showing my new design;

Fig. 2 is a rear elevational view thereof;

Fig. 3 is an end elevational view thereof;

Fig. 4 is a perspective view thereof in open position; and

Fig. 5 is an enlarged section along lines 5—5 of Fig. 4.

This drawing is shaded to show contrasting color areas.

I claim:

The ornamental design for a spectacle case, substantially as shown and described.
